RAILWAY TRAFFIC CONTROLLING APPARATUS

Maurice R. Williams, Richmond, Va., assignor to Westinghouse Air Brake Company, Wilmerding, Pa., a corporation of Pennsylvania

Application June 22, 1953, Serial No. 363,163

9 Claims. (Cl. 246—22)

My invention relates to railway traffic controlling apparatus. More particularly, my invention relates to apparatus of the type which is known as traffic locking apparatus, by means of which, traffic governing devices, such for example as signals for any given stretch of railway track, are in part manually controllable for governing traffic movements in both directions, and by means of which, traffic governing devices, after being controlled for governing traffic movements in one direction or the other over a stretch of railway track, cannot be controlled for governing traffic movements in the opposite direction while the stretch of track is occupied by a train, or while a traffic governing device, such for example as a signal, is controlled for authorizing a train to proceed in the former direction onto the stretch of track.

One form of traffic locking apparatus which has been used requires joint action by persons at two different control stations for manually controlling traffic movements in both directions over a stretch of railway track. Each of the two control stations may be provided with an interlocking machine, and each of the interlocking machines may be equipped with a traffic lever which is mechanically interlocked with a signal lever which controls a signal for governing traffic movements onto the corresponding end of the stretch of railway track.

In the particular form of apparatus shown embodying my invention, however, a traffic control circuit manually controllable from only one control station is employed, in which polar control relays are energized in series by current of one polarity or the other. The circuit also includes a contact of each of a plurality of track relays and other traffic controlled relays for a corresponding stretch of railway track and contacts of two time locking stick relays, one for each end of the stretch of track, controlled in conjunction with a signal for governing traffic movements entering the stretch of track at the corresponding end. Each of the polar control relays is of the magnetic stick type having polar contacts which, when the corresponding relay becomes deenergized, remain closed in the normal or the reverse position to which they were last operated in response to current of normal or reverse polarity, respectively.

Two track circuits, of the coded type, one for each direction of traffic movements, are provided for each track section between signals adjacent opposite ends of the stretch of track, which govern traffic movements off of the stretch of track. The track circuits for a given direction of traffic movements are set up by contacts of the polar control relays when closed in a given or normal position in response to energization of the polar control relays by current of a given normal polarity, and the track circuits for the opposite direction of traffic movement are set up by contacts of the polar control relays when closed in the opposite or reverse position in response to energization of the polar control relays by current of the opposite or reverse polarity.

In some forms of railway traffic controlling apparatus it is desirable, in order to save electric energy, that the track circuits shall be normally deenergized. In some forms of railway traffic controlling apparatus embodying coded track circuits it is further desirable, in order to reduce wear on the coding and decoding contacts, that the track circuits shall be normally deenergized.

An object of my invention, therefore, is the provision of means for keeping the coded or noncoded track circuits normally deenergized in some forms of railway traffic controlling apparatus such, for example, as that which is shown in the accompanying drawings.

A further object of my invention is the provision of means for effecting energization of coded or noncoded track circuits in response to operation of means for initiating the control of traffic governing devices such, for example, as signals for governing traffic movements in one direction or the other over the given stretch of railway track.

20 A feature of my invention for accomplishing these objects is the provision of means for effecting energization of the track circuits in response to deenergization of a corresponding traffic control circuit.

Another feature of my invention is the provision of means for deenergizing the traffic control circuit in response to operation of manually controllable means for initiating the control of traffic governing devices for governing traffic movements in one direction or the other over the given stretch of railway track.

30 Another feature of my invention is the provision of means for keeping the traffic control circuit deenergized while a train moves over the stretch of track.

Still another feature of my invention is the provision of means for again energizing the traffic control circuit when the given stretch of track becomes vacated.

I shall describe one form of apparatus embodying my invention, and shall then point out the novel features thereof in claims.

40 The accompanying drawings, Figs. 1a, 1b and 1c, when placed end to end in the order named, with Fig. 1a on the left, constitute a diagrammatic view showing one form of apparatus embodying my invention for a stretch of railway track which is provided with a plurality of signals spaced consecutively along the stretch of track for governing traffic movements over the stretch of railway track. The apparatus embodies a plurality of polar control relays, one for each of given signal locations, connected in series in a traffic control circuit. Each of the polar control relays has one or more contacts which, when the corresponding relay becomes deenergized, remain closed in the normal or the reverse position to which they were last previously operated in response to current of normal or of reverse polarity, respectively. 45 The control circuit also includes a plurality of neutral line relays, one for each polar control relay, connected in series with the polar control relays. The apparatus further embodies a plurality of line relay repeater relays, one for each of said neutral line relays and controlled by a front contact of the corresponding neutral line relay. A front contact of each of the line relay repeater relays is included in multiple with other relay contacts in the traffic control circuit and a back contact of each of the line relay repeater relays is included in a path connected in shunting relation around the control winding of the corresponding polar control relay. Energization of the traffic control circuit, including the polar control relays and the neutral line relays connected in series, by current of normal or reverse polarity, is manually controllable from only one control station, and contacts of traffic controlled relays are included in series with the control windings of the polar control relays and the 50 55 60 65 70

neutral line relays. Two normally deenergized track circuits of the coded type are provided for each of a plurality of track sections, one for each direction of traffic movement. The track circuits for a given direction of traffic movement are set up by contacts of the polar control relays, when closed in the given or normal position, and by back contacts of the neutral line relays, and the track circuits for the opposite direction of traffic movements are set up by contacts of the polar control relays when closed in the opposite or reverse position, and by back contacts of the neutral line relays.

Similar reference characters refer to similar parts in each of the drawings.

A stretch of railway track is illustrated, over which traffic movements are normally made from left to right, as shown in the drawings, which I shall assume is the east bound direction, but over which traffic movements may also at times be made in the opposite or westbound direction. In order to simplify the drawings, the track, comprising two parallel series of track rails, is represented by a single line.

The stretch of track is divided by insulated joints into sections, designated by the reference characters 1T, AT, BT and 5T. Each of the track sections 1T and 5T is provided with a track circuit including a suitable source of current such as a battery 7, connected across the rails adjacent one end of the section, and a track relay, designated by the reference character 1TR or 5TR, respectively, connected across the rails adjacent the opposite end of the section.

A suitable source of alternating current is provided such, for example, as an alternator, designated by the reference character L, shown in Fig. 1b, having terminals BX and NX.

Each of the track sections AT and BT is provided with a first track circuit which is at times supplied with coded alternating current adjacent the east end of the corresponding section for controlling eastbound traffic governing means, and with a second track circuit which is at times supplied with coded alternating current adjacent the west end of the corresponding section for controlling westbound traffic governing means. Each of the track circuits for section AT includes the winding *d* of a track transformer, designated by the reference character 3LT, connected across the rails adjacent the east end of the section, and the winding *d* of a track transformer, designated by the reference character 2RT, connected across the rails adjacent the west end of the section.

For controlling eastbound traffic governing means, the eastbound track circuit for section AT becomes energized by coded alternating current supplied to winding *m* of transformer 3LT from terminals BX and NX over front contacts of an eastbound traffic control relay, designated by the reference character 3EFP. A code following direct current track relay, which may be of the biased type operable by only current of the polarity indicated by the arrow in the symbol for the relay, for the eastbound track circuit for section AT, designated by the reference character 2RTR, becomes energized by current received from winding *m* of transformer 2RT over back contacts of a westbound traffic control relay, designated by the reference character 2WFP, through a rectifier, designated by the reference character 2RI.

For controlling westbound traffic governing means, the westbound track circuit for section AT becomes energized by alternating current supplied to winding *m* of transformer 2RT from terminals BX and NX over front contacts of the westbound traffic control relay 2WFP.

Another code following track relay, designated 3LTR and similar in every respect to relay 2RTR, is provided for this westbound track circuit. This relay becomes energized by current received from winding *m* of transformer 3LT over back contacts of eastbound traffic control relay 3EFP through a rectifier 3LI.

Each of the track circuits for section BT includes the winding *d* of a track transformer, designated by the reference character 4LT, connected across the rails adjacent the east end of the section, and the winding *d* of a track transformer, designated by the reference character 3RT, connected across the rails adjacent the west end of the section. The track circuits for section BT become energized in a manner similar to the track circuits for section AT, as already described, for controlling track relays, designated by the reference characters 3RTR and 4LTR, for controlling eastbound and westbound traffic governing means, respectively.

The rectifiers 2RI, 3RI, 3LI and 4LI may be of any suitable design such, for example, as the well-known bridge type comprising four asymmetric units, designated by the reference characters *i*1, *i*2, *i*3 and *i*4, which may be of the well-known copper oxide halfwave rectifier type.

Signals designated by the reference characters RA2 and L2 are located adjacent the opposite ends of track section 1T, and signals designated by the reference characters R4 and LA4 are located adjacent the opposite ends of track section 5T. A signal designated by the reference character R3 is located adjacent the adjoining ends of sections AT and BT. Signals RA2, R3 and R4 govern eastbound traffic movements, and signals L2 and LA4 govern westbound traffic movements. The signals may be of any suitable design such, for example, as the well-known color light type, each of which has green, yellow and red light units, designated by the reference characters G, Y and R, respectively, as shown in the drawings.

Track switches such as those designated by the reference characters 1 and 5 may be located in track sections 1T and 5T, respectively.

Operation of signals RA2, L2, R4 and LA4 and switches 1 and 5 may be controlled manually, at least in part, by manually operable devices such, for example, as interlocking machine levers, designated by the reference characters 2V and 4V. Each of the levers 2V and 4V has a normal position designated by the reference character *n*, in which it is shown in the drawings, and also a reverse position designated by the reference character *r* to the right, as shown in the drawings, and a reverse position designated by the reference character *f* to the left, as shown in the drawings.

A traffic lever, designated by the reference character FV, is also provided adjacent lever 2V, as shown in Fig. 1a. Lever FV has a normal position *n*, in which it is shown, and a reverse position *r* to the right, as shown in the drawing.

Contacts operated by levers 2V, 4V and FV are represented by circles, in each of which is placed a reference character to show the position of the corresponding lever in which the contact is closed. Contact 77 of lever 2V, for example, shown in the upper lefthand corner of Fig. 1a, is represented by a circle in which the reference character *r* is enclosed to show that contact 77 is closed while lever 2V is in its *r* position only. As another example, contact 16 of lever 2V, shown just below contact 77, is represented by a circle in which the reference character *nf* is enclosed to show that contact 16 is closed while lever 2V is in either its *n* or its *f* position or at any point between those two positions.

Time locking stick relays, designated by the reference characters 2AS and 4AS, are controlled in part by levers 2V and 4V, respectively, in conjunction with the control of signals by these levers.

Time element devices, shown as time element relays designated by the reference characters 2TE and 4TE, are associated with the control of relays 2AS and 4AS, respectively, by levers 2V and 4V, respectively. Each of the time element relays 2TE and 4TE is of a type having contacts which become closed only upon the lapse of

a measured period of time after the corresponding relay becomes energized.

A signal lighting relay, designated by the reference character RA2ER, is controlled in part by lever 2V for controlling signal RA2. Signal lighting relays, designated by the reference characters LA4ER and 4RER, are controlled in part by lever 4V for controlling signals LA4 and R4, respectively.

Polar control relays are provided, one for each of the given signal locations. Each of the polar control relays is designated by the reference character FR preceded by a numeral which is the same as that in the reference character for the corresponding signal.

Neutral line relays are also provided, one for each polar control relay. Each of the neutral line relays is designated by the reference character BPR preceded by a numeral which is the same as that in the reference character for the corresponding polar control relay.

Line relay repeater relays are provided, one for each neutral line relay. Each line relay repeater relay is designated by the reference character BPA preceded by a prefix which is the same as that in the reference character for the corresponding neutral line relay, and is controlled by a front contact of the corresponding neutral line relay.

The polar control relays and the neutral line relays are all connected in series in a traffic control circuit which includes front contacts of track relays 1TR and 5TR and front contacts of time locking stick relays 2AS and 4AS. This circuit may at times include front contacts of home signal relays which are designated by the reference character HR preceded by a distinguishing prefix, front contacts of traffic control relays which are designated by the reference character FP preceded by a distinguishing prefix, and front contacts of the line relay repeater relays.

The polar control relays and neutral line relays in the traffic control circuit are energized by current of normal or reverse polarity controlled by a master polar relay, designated by the reference character FSR, which is in turn controlled by pole-changing contacts of traffic lever FV. Under some conditions, the master polar relay FSR could be omitted, and energization of the polar control relays and neutral line relays by current of normal or reverse polarity could then be controlled directly by pole-changing contacts of traffic lever FV.

Each of the polar control relays FR, when energized by current of normal or reverse polarity, controls an eastbound or a westbound traffic control relay, respectively, designated by the reference characters EFP and WFP, respectively, preceded by a distinguishing numeral.

Code transmitting devices, each designated by the reference character CT, preceded by the reference character 75 or 180, may be of a type having a contact which, while the corresponding code transmitting device CT is energized, will open and close at a frequency of 75 or 180 times per minute, respectively. Each of the code transmitting devices CT is connected directly across the terminals of a suitable source of current, and therefore its contact is being repeatedly opened and closed at the frequency of 75 or 180 times per minute, as designated by the reference character of the corresponding device CT.

A decoding transformer, located at the west end and designated by the reference character 2T, has a primary winding *m* which is normally deenergized but becomes energized by pulses of current of alternately one polarity or the other controlled by relay 2RTR.

A home signal relay, designated by the reference character 2RHR, for signal RA2, is normally deenergized, but becomes energized by current of either the 75 or the 180 code frequency supplied from secondary winding *d* of transformer 2T through a rectifying contact 57 of relay 2RTR. A distant signal relay for signal RA2, designated by the reference character 2RDR, is normally

deenergized but becomes energized through a decoding unit, designated by the reference character 180DU, which is of a well-known type passing only current of the 180 code frequency. Relay 2RDR will therefore be operated only while winding *m* of transformer 2T is being energized by current of the 180 code frequency.

Decoding transformers, designated by the reference characters 3T and 4T for signals R3 and LA4, respectively, are normally deenergized but become energized similarly to transformer 2T as just described.

Home and distant signal relays, designated by the reference characters 3RHR and 3RDR, respectively, for signal R3, and by the reference characters 4LHR and 4LDR, respectively, for signal LA4, are operated similarly to relays 2RHR and 2RDR, as already described. A home signal relay, designated by the reference character 3LHR, becomes energized in response to operation of relay 3LTR by coded current. Each of the relays 2RHR, 3RHR and 4LHR is of a type which is slow to pick up and slow to release. Relay 3LHR is made slow to release by an asymmetric unit, designated by the reference character *i*5, connected in multiple with its control winding.

A suitable source of current such, for example, as a battery, designated by the reference character 2Q, having terminals designated by the reference characters 2B and 2N, is provided adjacent the west end of the stretch of track, and a suitable source of current such, for example, as a battery, designated by the reference character 4Q, having terminals designated by the reference characters 4B and 4N, is provided adjacent the east end of the stretch of track. A third suitable source of current such, for example, as a battery, designated by the reference character 3Q, having terminals designated by the reference characters 3B and 3N, is provided adjacent signal R3.

Having described, in general, the arrangement and control of the various parts of one form of apparatus embodying my invention, I shall now describe the circuits and operation in detail.

As shown in the drawings, each of the track sections 1T, AT, BT and 5T is unoccupied and relays 1TR and 5TR are energized. Each of the levers 2V and 4V is in the normal or *n* position, and therefore each of the signals RA2, L2, R4 and LA4 is displaying the red or stop indication. Signal R3 is also displaying the stop indication. Relays 2AS and 4AS are energized so that relays 2TE and 4TE are deenergized. Traffic control lever FV is in its *n* position, and therefore relay FSR is energized by current of normal polarity. With relay FSR energized by current of normal polarity, its pole-changing contacts 62 and 76 are closed in the normal position for energizing the polar control relays 2FR, 3FR and 4FR, and the neutral line relays 2BPR, 3BPR and 4BPR, by current of normal polarity. Relays 2EFP, 3EFP and 4EFP, and repeater relays 2BPA, 3BA, and 4BPA, are therefore also energized. As previously mentioned, each of the code transmitting devices 75CT and 180CT is constantly energized, and is therefore repeatedly closing and opening its contacts alternately at a frequency of 75 or 180 times per minute, respectively. The remaining relays shown, that is, relays 2RTR, 3RTR, 2RHR, 3RHR, 2RDR, 2WFP, RA2ER, 3WFP, 3LTR, 3LHR, 3RDR, LA4ER, 4RER, 4LDR, 4LHR, 4LTR, and 4WFP, are deenergized.

In Fig. 1a, code transmitting device 75CT is connected directly across terminals 2B and 2N, and is therefore repeatedly closing and opening its contact 87 at a frequency of 75 times per minute. In Fig. 1b, code transmitting devices 75CT and 180CT are connected directly across terminals 3B and 3N, and are therefore repeatedly closing and opening their contacts at a frequency of 75 and 180 times, respectively, per minute. In Fig. 1c, code transmitting devices 75CT and 180CT are connected directly across terminals 4B and 4N, and are therefore

repeatedly closing and opening their contacts at a frequency of 75 and 180 times, respectively, per minute.

In Fig. 1a, red lamp R of signal RA2 is shown lighted by a circuit passing from terminal 2B, through the back point of contact 8 of relay RA2ER, and lamp R of signal RA2 to terminal 2N. The red lamps of signals L2, R4 and LA4 are also lighted by circuits which are similar to the circuit just traced for signal RA2.

In Fig. 1b, red lamp R of signal R3 is shown lighted by a circuit passing from terminal 3B, through the front point of contact 13 of relay 3EFP, back point of contact 14 of relay 3RHR, and lamp R of signal R3 to terminal 3N.

As shown in Fig. 1a, relay 2AS is energized by a stick circuit passing from terminal 2B, through contact 16 of lever 2V, contact 17 of relay RA2ER, front point of contact 18 of relay 2AS, and the winding of relay 2AS to terminal 2N. Relay 4AS, shown in Fig. 1c, is also energized by a similar stick circuit.

Relay FSR is energized by current of normal polarity passing from terminal 2B, through contact 26 of lever FV, winding of relay FSR, and contact 27 of lever FV to terminal 2N. Relays 2BPR, 2FR, 3FR, 3BPR, 4FR and 4BPR are therefore energized by current of normal polarity in a circuit which will be traced later. The polar contacts of each of the relays 2FR, 3FR and 4FR are therefore closed in the normal position.

With relay 2BPR energized, relay 2BPA is energized by an obvious circuit passing from terminal 2B, through contact 100 of relay 2BPR, and the winding of relay 2BPA to terminal 2N. Each of the relays 3BPA and 4BPA is energized by a similar circuit including contact 100 of relays 3BPR and 4BPR, respectively.

With contact 30 of relay 4FR closed in the normal position, relay 4EFP is energized by both a pickup and a stick circuit, the pickup circuit passing from terminal 4B, through contact 39 of relay 4FR closed in the normal position, contacts 31 and 32 of relays 4AS and 5TR, respectively, contact 34 of relay 4WFP, and the winding of relay 4EFP to terminal 4N. The stick circuit is the same as the pickup circuit just traced except that it includes contact 33 of relay 4EFP instead of contacts 31 and 32 of relays 4AS and 5TR.

With contact 44 of relay 3FR closed in the normal position, relay 3EFP is energized by a stick circuit passing from terminal 3B, through contact 44 of relay 3FR in the normal position, contact 46 of relay 3EFP, contact 47 of relay 3WFP, and the winding of relay 3EFP to terminal 3N.

With the polar contact 58 of relay 2FR closed in the normal position, relay 2EFP is energized by a stick circuit passing from terminal 2B, through contact 58 of relay 2FR in its normal position, contacts 60 and 61 of relays 2EFP and 2WFP, respectively, and the winding of relay 2EFP to terminal 2N.

Each of the relays EFP and WFP is of the slow release type.

The circuit by which the BPR and FR relays are energized by current of normal polarity passes from terminal 2B, through contact 62 of relay FSR closed in the normal position, contacts 63 and 64 of relays 1TR and 2AS, respectively, windings of relays 2BPR and 2FR, from point of contact 65 of relay 2BPA, front point of contact 70 of relay 3BPA, windings of relays 3FR and 3BPR, front point of contact 73 of relay 4BPA in multiple with contact 71 of relay 4EFP, windings of relays 4FR and 4BPR, contacts 74 and 75 of relays 4AS and 5TR, respectively, and contact 76 of relay FSR closed in the normal position, to terminal 2N.

I shall assume that a leverman moves lever 2V to the *r* position in order to clear signal RA2 for an eastbound train. When the leverman moves lever 2V away from its *n* position toward the *r* position, contact 16 of lever 2V will become opened, thereby deenergizing relay 2AS.

Upon deenergization of relay 2AS, contact 64 of this

relay will open the circuit previously traced for the BPR and FR relays, causing these relays to become deenergized. The deenergization of the BPR relays, with the resulting opening of their contacts 100, causes the associated repeater relays BPA to also be deenergized. Each BPA relay, upon becoming deenergized, completes a shunt circuit around the winding of the corresponding polar relay FR. For example, closing of back contact 65 of relay 2BPA shunts the winding of relay 2FR. Back contacts 70 and 73 of relays 3BPA and 4BPA, respectively, provide similar shunting circuits for the windings of relays 3FR and 4FR. These shunt circuits prevent the operation or reversal of the contacts of the polar relays due to foreign current or spurious surges in the line circuit while a signal is cleared or while a train is traversing the stretch of track. This feature is more fully explained and is claimed in the pending application for Letters Patent of the United States, Serial No. 314,843, by John M. Pelikan, filed October 15, 1952, for Railway Traffic Controlling Apparatus.

Relay 4BPR, upon becoming deenergized, will complete a circuit for energizing primary winding *m* of transformer 4LT, this circuit passing from terminal BX, through contact 101 of relay 4BPR, contact 35 of code transmitting device 75CT, back point of contact 37 of relay 4RER, front point of contact 38 of relay 4EFP, winding *m* of transformer 4LT, and the front point of contact 39 of relay 4EFP to terminal NX. Alternating current, coded at the frequency of 75 times per minute, is therefore supplied by winding *d* of transformer 4LT over the rails of section BT to winding *d* of transformer 3RT.

With transformer 3RT thus energized, relay 3RTR is energized by circuit means including winding *m* of transformer 3RT, back point of contact 41 of relay 3WFP, rectifier 3RI, winding of relay 3RTR, and the back point of contact 40 of relay 3WFP. With relay 3RTR thus energized by current coded at the frequency of 75 times per minute, primary winding *m* of transformer 3T is being repeatedly energized by current pulses of normal and reverse polarity alternately. The circuit by which the pulses of normal polarity are supplied to winding *m* of transformer 3T passes from terminal 3B, through the front point of contact 42 of relay 3RTR, and the middle portion of winding *m* of transformer 3T to terminal 3N. The circuit by which the pulses of reverse polarity are supplied to winding *m* of transformer 3T passes from terminal 3B, through the back point of contact 42 of relay 3RTR, and the lowest portion of winding *m* of transformer 3T, as shown in the drawing, to terminal 3N.

Relay 3RHR is therefore energized by current passing from winding *d* of transformer 3T through a rectifying contact 43 of relay 3RTR. With winding *m* of transformer 3T energized by pulses of current of normal and reverse polarities at the frequency of 75 times per minute, relay 3RDR will not be energized, since current of this frequency cannot pass through the corresponding decoding unit 186DU. With relays 3EFP and 3RHR energized and relay 3RDR deenergized, lamp Y of signal R3 is lighted by a circuit passing from terminal 3B, through the front point of contact 13 of relay 3EFP, front point of contact 14 of relay 3RHR, back point of contact 15 of relay 3RDR, and lamp Y of signal R3 to terminal 3N.

With contact 44 of relay 3FR closed in the normal position, and with relay 3RHR energized, a pickup circuit will be completed for relay 3EFP which is, however, already energized by its stick circuit previously traced. The pickup circuit for relay 3EFP passes from terminal 3B, through contact 44 of relay 3FR closed in the normal position, contact 45 of relay 3RHR, contact 47 of relay 3WFP, and the winding of relay 3EFP to terminal 3N.

With relays 3RHR and 3EFP energized and relay 3BPR deenergized, winding *m* of transformer 3LT will be energized by alternating current coded at the frequency of 180 times per minute in a circuit passing from terminal BX, through the front point of contact 48 of relay 3EFP, winding *m* of transformer 3LT, front point of contact 49

of relay 3EFP, contact 50 of code transmitting device 180CT, front point of contact 53 of relay 3RHR, and contact 191 of relay 3BPR to terminal NX. Alternating current, coded at the frequency of 180 times per minute, is therefore supplied from winding d of transformer 3LT over the rails of section AT to winding d of transformer 2RT.

Relay 2RTR is therefore energized by a circuit including winding m of transformer 2RT, the back point of contact 55 of relay 2WFP, rectifier 2RI, winding of relay 2RTR, and the back point of contact 54 of relay 2WFP. With relay 2RTR thus energized by current coded at the frequency of 180 times per minute, winding m of transformer 2T is energized by current of normal and reverse polarity alternately at the frequency of 180 times per minute. Both relays 2RHR and 2RDR are therefore energized.

With relay 2RHR energized, a pickup circuit will now be completed for relay 2EFP which is, however, already energized by its stick circuit. The pickup circuit for relay 2EFP passes from terminal 2B, through contact 58 of relay 2FR closed in the normal position, contact 59 of relay 2RHR, contact 61 of relay 2WFP, and the winding of relay 2EFP to terminal 2N.

With relay 2RHR now energized while lever 2V is in the r position, relay RA2ER will become energized by a circuit passing from terminal 2B, through contact 77 of lever 2V, contacts 78 and 79 of relays 1TR and 2FR, respectively, contact 80 of relay 2RHR, and the winding of relay RA2ER to terminal 2N. With relay RA2ER energized, contact 8 of this relay will become open, at its back point, thereby extinguishing lamp R of signal RA2, and will become closed at its front point, thereby completing a circuit for lighting green lamp G of signal RA2, this circuit passing from terminal 2B, through the front point of contact 8 of relay RA2ER, front point of contact 9 of relay 2RDR, and lamp G of signal RA2 to terminal 2N.

I shall assume further that, before the eastbound train passes signal RA2, the leverman decides to stop the train at this signal. He will therefore return lever 2V to its n position, thereby deenergizing relay RA2ER and thus causing green lamp G of signal RA2 to become extinguished and lamp R of this signal to again be lighted. With lever 2V again in its n position and relay RA2ER deenergized, an energizing circuit will be completed for time element relay 2TE, this circuit passing from terminal 2B, through contact 16 of lever 2V, contact 17 of relay RA2ER, back point of contact 18 of relay 2AS, and relay 2TE to terminal 2N.

Upon the lapse of a measured period of time, relay 2TE will close its front contact 19, thereby completing a pickup circuit for relay 2AS, this circuit passing from terminal 2B, through contact 16 of lever 2V, contact 17 of relay RA2ER, contact 19 of relay 2TE, and the winding of relay 2AS to terminal 2N. Relay 2AS, upon becoming energized by its pickup circuit, will again complete its stick circuit previously traced, and will also complete, at its contact 64, a circuit for energizing the BPR relays. This circuit for the BPR relays passes from terminal 2B, through contact 62 of relay FSR closed in the normal position, contacts 63 and 64 of relays 1TR and 2AS, respectively, winding of relay 2BPR, winding of relay 2FR in multiple with a shunt path through the back point of contact 65 of relay 2BPA, contact 66 of relay 2RHR, contact 68 of relay 3RHR, winding of relay 3FR in multiple with a shunt path through the back point of contact 70 of relay 3BPA, winding of relay 3BPR, contact 71 of relay 4EFP, winding of relay 4FR in multiple with a shunt path through the back point of contact 73 of relay 4BPA, winding of relay 4BPR, contacts 74 and 75 of relays 4AS and 5TR, respectively, and contact 76 of relay FSR closed in the normal position to terminal 2N.

With the BPR relays again energized, contact 101 of

75

each of the relays 3BPR and 4BPR will open the eastbound track circuits previously traced for sections AT and BT, respectively, causing these track circuits to become deenergized. Relays 3RHR, 2RHR and 2RDR will therefore also in turn become deenergized. With the BPR relays again energized, the BPA relays will in turn also again become energized by their circuits previously described. The back points of the BPA relays will then become opened in the shunt paths around the windings of the FR relays which will therefore become energized. The front points of the contacts of the BPA relays will become closed before contacts 66 and 68 of relays 2RHR and 3RHR become opened. The BPR and FR relays will then be energized by the circuit first traced for these relays.

I shall assume that the leverman later decides to again clear signal RA2 for the eastbound train. He will therefore again move lever 2V to its r position, causing relay 2AS to again become deenergized and thereby open, at its contact 64, the traffic direction control circuit arrangement including the FR and BPR relays. The BPR relays will therefore again be deenergized, and the eastbound track circuits for sections AT and BT will again become energized as previously described, and lamp Y of signal R3 will again become lighted. Lamp G of signal RA2 will also again become lighted, as previously described.

When the eastbound train enters section 1T, deenergizing relay 1TR, contact 78 of this relay will open the circuit previously traced for relay RA2ER, causing relay RA2ER to become deenergized. Lamp G of signal RA2 will therefore be extinguished and lamp R will again be lighted. When relay 1TR becomes deenergized, its contact 63 opens the circuit for the BPR and FR relays at another point.

If, now, while the train is on section 1T, the leverman returns lever 2V to its n position, relay 2AS will become energized by a second pickup circuit, this circuit passing from terminal 2B, through contact 16 of lever 2V, contact 17 of relay RA2ER, contact 20 of relay 1TR, and the winding of relay 2AS to terminal 2N. With relay 2AS again energized, its contact 64 will be closed in the circuit for the BPR relays, but this circuit will still be open at contact 63 of relay 1TR.

If it is decided to permit the eastbound train to continue its movement past signal R4 at the east end of the stretch, a leverman will move lever 4V to its r position, thereby completing a circuit for energizing relay 4RER, this circuit passing from terminal 4B, through contact 81 of lever 4V, contact 82 of relay 5TR, and the winding of relay 4RER to terminal 4N. With relay 4RER thus energized, its contact 12 will open the circuit for the red lamp R of signal R4, and, at its front point, will complete a circuit for lighting either lamp Y or lamp G of this signal, according to traffic conditions in advance, as indicated by the dotted portion of the circuits controlled by the front point of contact 12 of relay 4RER.

With relay 4RER energized, alternating current, coded at the frequency of 180 times per minute will be supplied to winding m of transformer 4LT over a circuit passing from terminal BX, through contact 101 of relay 4BPR, contact 36 of code transmitting device 180CT, front point of contact 37 of relay 4RER, front point of contact 38 of relay 4EFP, winding m of transformer 4LT, and the front point of contact 39 of relay 4EFP to terminal NX. Winding d of transformer 4LT will therefore supply alternating current, coded at the frequency of 180 times per minute, to the rails of section B1, for energizing winding d of transformer 3RT.

Relay 3RTR will therefore now be energized by current coded at the frequency of 180 times per minute, so that winding m of transformer 3T will now be energized by current of normal and reverse polarity alternately at the frequency of 180 times per minute. Relay 3RHR will therefore be energized as before, and, in addition, relay 3RDR will be energized by current of the 180 code fre-

quency passing through the decoding unit 180DU. When relay 3RDR becomes energized, its contact 15 will open, at its back point, thereby extinguishing lamp Y of signal R3, and will become closed at its front point, thereby completing a circuit for lighting lamp G of signal R3, this circuit passing from terminal 3B, through the front point of contact 13 of relay 3EFP, front point of contact 14 of relay 3RHR, front point of contact 15 of relay 3RDR, and lamp G of signal R3 to terminal 3N.

The eastbound train, upon entering section AT, will de-energize winding *d* of transformer 2RT, which in turn will cause relay 2RTR to become deenergized, and then transformer 2T and relays 2RDR and 2RHR will also become deenergized. Relay 2RHR, upon becoming deenergized, opens the pickup circuit for relay 2EFP, which, however, remains energized by its stick circuit. When relay 2RHR becomes deenergized, its contact 80 opens the circuit for relay RA2ER at another point, and its contact 66 also opens the circuit for relays BPR and FR at another point.

With the circuit for relays BPR and FR open, and therefore deenergized, relays BPA will also be deenergized, because contact 100 of each of the BPR relays will be open. Contacts 65, 70 and 73 of relays 2BPA, 3BPA and 4BPA, respectively, will be open at their front points in the circuits for the BPR and FR relays and the back points of these contacts will be closed in the shunt paths around the windings of relays 2FR, 3FR and 4FR, respectively.

When the train leaves section 1T, relay 1TR will become energized, thereby opening its contact 20 in the second pickup circuit traced for relay 2AS which will then remain energized by its stick circuit. Contact 78 of relay 1TR will now again be closed in the circuit for relay RA2ER, and contact 63 of relay 1TR will again be closed in the circuit for the BPR and FR relays.

When the train enters section BT, winding *d* of transformer 3RT will become deenergized, causing relay 3RTR to become deenergized, and in turn causing transformer 3T and relays 3RHR and 3RDR to also be deenergized. The pickup circuit for relay 3EFP will now be open at contact 45 of relay 3RHR, but relay 3EFP will remain energized by its stick circuit.

When relay 3RHR becomes deenergized, its contact 68 will open the circuit for the BPR and FR relays at another point, and its contact 53 will open, at its front point, the circuit previously traced for energizing winding *m* of transformer 3LT by current coded at the frequency of 180 times per minute. A circuit will now be completed for energizing winding *m* of transformer 3LT by current coded at the frequency of 75 times per minute, this circuit passing from terminal BX, through the front point of contact 48 of relay 3EFP, winding *m* of transformer 3LT, from point of contact 49 of relay 3EFP, contact 51 of code transmitter 75CT, back point of contact 52 of relay 3LHR, back point of contact 53 of relay 3RHR, and contact 101 of relay 3BPR to terminal NX. When relay 3RHR becomes deenergized, its contact 14 will open, at its front point, the circuit previously traced for lamp G of signal R3, causing this lamp to be extinguished, and will complete the circuit previously traced for lighting lamp R of signal R3.

When the train leaves section AT, winding *d* of transformer 2RT will become energized by current coded at the frequency of 75 times per minute, causing relay 2RTR to in turn become energized by current coded at this frequency. Relay 2RHR will therefore again be energized, but relay 2RDR will remain deenergized. With relay 2RHR again energized, the pickup circuit for relay 2EFP will again become closed at contact 59 of relay 2RHR. Also, with relay 2RHR again energized, its contact 66 will again be closed in the circuit for relays BPR and FR, and contact 30 of relay 2RHR will again be closed in the circuit traced for relay RA2ER.

If desired, the leverman can now control signal RA2

75

to display a yellow or caution indication for a second eastbound train to pass signal RA2. He will accomplish this by again moving lever 2V to the *r* position, thereby causing relay RA2ER to again become energized by its circuit previously traced. With relay RA2ER again energized, while relay 2RDR is deenergized, a circuit will be completed for lighting yellow lamp Y of signal RA2, this circuit passing from terminal 2B, through the front point of contact 8 of relay RA2ER, back point of contact 9 of relay 2RDR, and lamp Y of signal RA2 to terminal 2N.

When the first eastbound train enters section 5T, relay 5TR will become deenergized, causing relay 4RER to become deenergized, and in turn causing lamp G or lamp Y of signal R4 to be extinguished, and lamp R of this signal to again be lighted. Contact 75 of relay 5TR will now be open in the circuit for the BPR and FR relays. The pickup circuit traced for relay 4EFP will be opened at contact 32 of relay 5TR, but relay 4EFP will remain energized by its stick circuit previously traced. With relay 4RER again deenergized, winding *m* of transformer 4LT will be supplied with current coded at the frequency of 75 times per minute, as previously described.

When the first eastbound train leaves section BT, winding *d* of transformer 3RT will again be energized by current coded at the frequency of 75 times per minute, causing relay 3RTR to in turn become energized by current coded at this frequency, so that transformer 3T and relay 3RHR will also be energized, but relay 3RDR will not become energized. Red lamp R of signal R3 will now be extinguished because of the opening of contact 14 of relay 3RHR at its back point, and the yellow lamp Y of this signal will again become lighted by the circuit previously traced.

When both eastbound trains have proceeded beyond signal LA4, and have left section 5T, the circuit previously traced for energizing the BPR relays will be completed, including the back points of contacts 65, 70 and 73 of relays 2BPA, 3BPA and 4BPA, respectively, in shunt paths around the windings of relays 2FR, 3FR and 4FR, respectively, and including contacts 66 and 68 of relays 2RHR and 3RHR, respectively. The BPR relays, upon again becoming energized, will complete the circuits for energizing the corresponding BPA relays, causing these relays to also become energized. Relays 2BPA, 3BPA, and 4BPA, upon becoming energized, will open their contacts 65, 70 and 73 respectively, at their back points, and will again close these contacts at their front points, so that relays 2FR, 3FR and 4FR will again be energized by the circuit first traced for the PBR and FR relays. All parts of the apparatus will then again be in the condition shown in the drawings.

I shall next assume that a westbound train is to move over the stretch of track shown in the drawings. A leverman will therefore move lever FV to its *r* position, causing relay FSR to become energized by current of reverse polarity passing from terminal 2B, through contact 28 of lever FV, winding of relay FSR, and contact 29, of lever FV to terminal 2N. Contacts 62 and 76 of relay FSR will therefore be moved to the reverse position. While these contacts are moving from the normal to the reverse position, the BPR and FR relays will become deenergized, causing the BPA relays to also become deenergized. Since the BPA relays as shown in the drawings are of the slow release type, the front points of the contacts of these relays will not become open because of the deenergization of the BPR relays during the movement of the contacts 62 and 76 of relay FSR from the normal to the reverse position. If contacts 62 and 76 of relay FSR move quickly enough between their extreme positions, the front points of the contacts of the BPA relays would not become open even if the BPA relays were not of the slow release type. When contacts 62 and 76 of relay FSR reach their reverse positions, a circuit will be completed for energizing the BPR and FR relays by current of re-

verse polarity which is otherwise the same as the circuit first traced for energizing the BPR and FR relays through the front points of the contacts of the BPA relays.

Each of the polar relays 2FR, 3FR and 4FR, upon becoming energized by current of reverse polarity, will immediately move its polar contacts to the reverse position, thereby deenergizing the corresponding EFP relays. However, the release time of the BPA relays is such that their front contacts open before the slower acting neutral BPR relays, reenergized by current of reverse polarity, can reclose their front contacts 100 to hold the BPA relays energized. Thus the traffic control circuit is interrupted at front contacts 65, 70, and 73 of the BPA relays and the BPR and FR relays are again deenergized. The release of each BPA relay completes a shunt circuit around the winding of the associated FR relay to assure that the FR relay remains in its selected position regardless of transient currents which may appear in the line circuit. As hereinbefore discussed, this matter is fully explained in the pending Pelikan application Serial No. 314,843.

A pickup circuit will now be completed for energizing relay 2WFP, this circuit passing from terminal 2B, through contact 58 of relay 2FR closed in the reverse position, contacts 83 and 84 of relays 2AS and 1TR, respectively, contact 85 of relay 2EFP, and the winding of relay 2WFP to terminal 2N. Relay 2WFP, upon becoming energized by its pickup circuit, will complete its stick circuit, which is the same as the pickup circuit just traced except that it includes contact 86 of relay 2WFP instead of contacts 83 and 84 of relays 2AS and 1TR, respectively.

With relay 2BPR deenergized and relay 2WFP energized, winding m of transformer 2RT will be energized by current coded at the frequency of 75 times per minute supplied to a circuit passing from terminal BX, through contact 101 of relay 2BPR, contact 87 of code transmitting device 75CT, front point of contact 54 of relay 2WFP, winding m of transformer 2RT, and the front point of contact 55 of relay 2WFP to terminal NX. Winding d of transformer 3LT will therefore now be energized by current coded at the frequency of 75 times per minute and supplied over the rails of section AT from winding d of transformer 2RT.

A circuit will now be completed for energizing relay 3LTR from winding m of transformer 3LT, this circuit including winding m of transformer 3LT, back point of contact 49 of relay 3EFP, rectifier 3LI, winding of relay 3LTR, and the back point of contact 48 of relay 3EFP. Relay 3LTR will therefore now be periodically energized at a frequency of 75 times per minute, causing contact 88 of relay 3LTR to be closed at its front and back points alternately.

Each time contact 88 of relay 3LTR becomes closed at its back point, a circuit will be completed for charging an energy storing device, designated by the reference character e , this circuit passing from terminal 3B, through the back point of contact 88 of relay 3LTR, energy storing device e , and a resistor t to terminal 3N. Each time contact 88 of relay 3LTR becomes closed at its front point, the energy storing device e will discharge through the winding of relay 3LHR, the circuit passing from device e , through the front point of contact 88 of relay 3LTR, winding of relay 3LHR, and resistor t back to device e . Relay 3LHR is made slow releasing by an asymmetric unit $i5$ connected in multiple with its control winding, and therefore its front contacts 52, 69 and 89 will remain closed while contact 88 of relay 3LTR is being closed alternately at its front and back points.

A pickup circuit will now be completed for relay 3WFP, passing from terminal 3B, through contact 44 of relay 3FR closed in the reverse position, contact 89 of relay 3LHR, contact 91 of relay 3EFP, and the winding of relay 3WFP to terminal 3N. Relay 3WFP, upon becoming energized, will complete its stick circuit, which is the same as the pickup circuit just traced except that it in-

cludes contact 90 of relay 3WFP instead of contact 89 of relay 3LHR.

A circuit will then be completed for energizing winding m of transformer 3RT by current coded at the frequency of 180 times per minute, this circuit passing from terminal BX, through the front point of contact 40 of relay 3WFP, winding m of transformer 3RT, front point of contact 41 of relay 3WFP, contact 50 of code transmitting device 180CT, front point of contact 52 of relay 3LHR, back point of contact 53 of relay 3RHR, and contact 101 of relay 3BPR to terminal NX. Current coded at the frequency of 180 times per minute will therefore now be supplied from winding d of transformer 3RT over the rails of section BT, to winding d of transformer 4LT.

Relay 4LTR will be energized by current coded at the frequency of 180 times per minute in a circuit which includes winding m of transformer 4LT, back point of contact 39 of relay 4EFP, rectifier 4LI, winding of relay 4LTR, and the back point of contact 38 of relay 4EFP. Transformer 4T and relays 4LHR and 4LDR will therefore now be energized through contacts 92 and 93 of relay 4LTR while being repeatedly closed at their front and back points alternately at the frequency of 180 times per minute.

With relay 4LHR energized, a pickup circuit will be completed for relay 4WFP, this circuit passing from terminal 4B, through contact 30 of relay 4FR closed in the reverse position, contact 94 of relay 4LHR, contact 96 of relay 4EFP, and the winding of relay 4WFP to terminal 4N. Relay 4WFP, upon becoming energized by its pickup circuit, will complete its stick circuit, which is the same as the pickup circuit just traced except that it includes contact 95 of relay 4WFP instead of contact 94 of relay 4LHR.

With relay 4LHR energized, the traffic control circuit is once again completed and the relays BPR energized. The circuit is traced from terminal 2B through contact 76 of relay FSR closed in its reverse position, contacts 75 and 74 of relays 5TR and 4AS, respectively, the winding of relay 4BPR, back contact 73 of relay 4BPA in multiple with the winding of relay 4FR, contact 72 of relay 4LHR, the winding of relay 3BPR, back contact 70 of relay 3BPA in multiple with the winding of relay 3FR, contact 69 of relay 3LHR, contact 67 of relay 2WFP, back contact 65 of relay 2BPA in multiple with the winding of relay 2FR, the winding of relay 2BPR, contacts 64 and 63 of relays 2AS and 1TR, respectively, and contact 62 of relay FSR closed in its reverse position, to terminal 2N. The BPR relays are thus energized, and close their contacts 100 to reenergize the BPA relays. When the BPA relays open their back contacts, the shunts are removed from the winding of the FR relays which are then energized with current of reverse polarity. Since the contacts of these relays already are closed in the reverse position, no further action occurs.

The opening of back contacts 101 of the BPR relays deenergizes the track circuits. However, since relays 3LHR and 4LHR are of the slow release type, the opening of contacts 69 and 72, respectively, in the traffic control circuit is sufficiently delayed that front contacts 70 and 73 of relays 3BPA and 4BPA, respectively, are closed in time to maintain the BPR and FR relays energized. Front contact 65 of relay 2BPA, when closed, is in multiple with contact 67 of relay 2WFP. Thus, at this time the traffic control circuit is so energized as to permit a westward train movement if desired.

I shall now assume that a leverman or dispatcher moves lever 4V to the f position to initiate the clearing of signal LA4 for a westbound traffic movement. Contact 21 of lever 4V will therefore open the circuits for relay 4AS, causing relay 4AS to be deenergized. With relay 4AS deenergized, its contact 74 will open the traffic direction control circuit including the BPR and FR relays, causing these relays to be deenergized. With the BPR relays deenergized, and the WFP relays energized, the

westbound track circuits will be energized, in a manner similar to that just described during the reversal of traffic direction. If the lever 4V is moved to its *f* position immediately after the lever FV is moved to its *r* position, the traffic control circuit will not be reenergized at the end of the reversal of traffic; but rather the track circuits will remain energized and the signal LA4 will immediately clear, as described in the succeeding paragraph.

With lever 4V occupying its *f* position, and relay 4LHR energized, a circuit is completed to energize relay LA4ER. This circuit is traced from terminal 4B through contact 97 of lever 4V, contact 98 of relay 4FR, contact 99 of relay 4LHR, and the winding of relay LA4ER to terminal 4N. Signal LA4 will now be controlled to display a green or clear proceed indication for westbound traffic. The circuit for lighting lamp G is traced from terminal 4B through the front points of contacts 10 and 11 of relays LA4ER and 4LDR, respectively, and lamp G to terminal 4N.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In railway traffic controlling apparatus embodying traffic governing means for directing traffic movements in both directions over a given stretch of railway track, including a normally energized traffic direction control circuit which is manually controlled at only one location to establish traffic direction, the combination comprising, first manually controllable means operable for initiating the control of said traffic governing means for governing traffic movements in a given direction over said given stretch of track, second manually controllable means operable for initiating the control of said traffic governing means for governing traffic movements in the opposite or second direction over said given stretch of track, means controlled by operation of each of said first and second manually controllable means for deenergizing said traffic direction control circuit, traffic responsive means for said given stretch of track, means controlled by said traffic direction control circuit upon becoming deenergized for effecting energization of said traffic responsive means, said traffic responsive means then becoming deenergized in response to traffic movements on said stretch of track, and means controlled by operation of said manually controllable means and by said traffic responsive means upon becoming energized in response to operation of said first or said second manually controllable means for effecting operation of said traffic governing means for directing traffic movements in said first or second direction respectively over said given stretch of track.

2. In railway traffic controlling apparatus embodying traffic governing means for directing traffic movements in both directions over a given stretch of railway track, including a traffic direction control circuit which is normally energized by current of a given polarity or of the opposite polarity, the polarity being manually controlled at only one selected location, the combination comprising, first manually controllable means operable for initiating the control of said traffic governing means for governing traffic movements in a given direction over said given stretch of track, second manually controllable means operable for initiating the control of said traffic governing means for governing traffic movements in the opposite or second direction over said given stretch of track, means controlled by operation of each of said first and second manually controllable means for deenergizing said traffic direction control circuit, traffic responsive means for said given stretch of track, means controlled

by said traffic direction control circuit upon becoming deenergized for effecting energization of said traffic responsive means, said traffic responsive means then becoming deenergized in response to traffic movements on said stretch of track, means controlled by said traffic responsive means for them retaining said traffic direction control circuit deenergized while said stretch of track is occupied, and means controlled by operation of said manually controllable means and by said traffic responsive means upon becoming energized in response to operation of said first or said second manually controllable means for effecting operation of said traffic governing means for directing traffic movements in said first or second direction respectively over said given stretch of track.

3. In railway traffic controlling apparatus for a stretch of railway track which is divided into a plurality of sections and is provided with a plurality of traffic governing devices spaced consecutively along said stretch for governing traffic movements in a first direction and in the opposite or second direction, embodying a plurality of polar control relays connected in series in a traffic direction control circuit, each of said relays having polar contacts which when the corresponding relay becomes deenergized remain closed in a normal or a reverse position to which they were last operated in response to current of normal or reverse polarity respectively, in which energization of said traffic control circuit including said polar control relays connected in series by current of normal and reverse polarities is manually controllable, in which traffic responsive means is provided for each of said track sections, in which energization of said traffic responsive means for each of given sections for a given direction of traffic movements is controlled by contacts of said polar control relays when closed in the normal position and energization of said traffic responsive means for the opposite direction of traffic movements is controlled by contacts of said polar control relays when closed in the reverse position, in which said traffic control circuit includes contact means controlled by said traffic responsive means and closed only while said traffic responsive means is energized, said traffic responsive means becoming deenergized in response to occupancy of said stretch of track by a train, and in which each of said traffic governing devices is controlled by corresponding said traffic responsive means and by manually operable means, the combination comprising, a plurality of neutral line relays one adjacent each of said polar control relays connected in series with said polar control relays and said contact means controlled by said traffic responsive means in said traffic control circuit, means controlled by said manually operable means when said manually operable means is manipulated for controlling said traffic governing devices for deenergizing said traffic control circuit, and back contacts of said neutral line relays included in the means for energizing said traffic responsive means.

4. In railway traffic controlling apparatus for a stretch of railway track which is divided into a plurality of sections and is provided with a plurality of traffic governing devices spaced consecutively along said stretch for governing traffic movements in a first direction and in the opposite or second direction, embodying a plurality of polar control relays connected in series in a traffic direction control circuit, each of said relays having polar contacts which when the corresponding relay becomes deenergized remain closed in a normal or a reverse position to which they were last operated in response to current of normal or reverse polarity respectively, in which energization of said traffic control circuit including said polar control relays connected in series by current of normal and reverse polarities is manually controllable, in which traffic responsive means is provided for each of said track sections, in which energization of said traffic responsive means for each of given sections for a given direction of traffic movements is controlled by contacts of said polar control

relays when closed in the normal position and energization of said traffic responsive means for the opposite direction of traffic movements is controlled by contacts of said polar control relays when closed in the reverse position, in which said traffic direction control circuit includes contact means controlled by said traffic responsive means and closed only while said traffic responsive means is energized, said traffic responsive means becoming deenergized in response to occupancy of said stretch of track by a train, and in which each of said traffic governing devices is controlled by corresponding said traffic responsive means and by manually operable means, the combination comprising, a plurality of neutral line relays one adjacent each of said polar control relays connected in series with said polar control relays and said contact means controlled by said traffic responsive means in said traffic control circuit, means controlled by said manually operable means when said manually operable means is manipulated for controlling said traffic governing devices for deenergizing said traffic control circuit, back contacts of said neutral line relays included in the means for energizing said traffic responsive means, a plurality of line relay repeater relays one for each of said neutral line relays, means controlled by a front contact of each of said neutral line relays for energizing the corresponding line relay repeater relay, and front contacts of said line relay repeater relays connected in multiple with said contact means controlled by said traffic responsive means in said traffic control circuit.

5. In railway traffic controlling apparatus for a stretch of railway track which is divided into a plurality of sections and is provided with a plurality of traffic governing devices spaced along said stretch for governing traffic movements in a first direction and in the opposite or second direction, embodying a plurality of polar control relays connected in series in a traffic control circuit, each of said relays having polar contacts which when the corresponding relay becomes deenergized remain closed in a normal or a reverse position to which they were last operated in response to current of normal or reverse polarity respectively, in which energization of said traffic control circuit including said polar control relays connected in series by current of normal and reverse polarities is manually controllable, in which two track circuits are provided for each of given sections one for each direction of traffic movements, in which energization of each of the track circuits for a given direction of traffic movements is controlled by a contact of a corresponding polar control relay when closed in the normal position and energization of each of the track circuits for the opposite direction of traffic movements is controlled by a contact of a corresponding polar control relay when closed in the reverse position, in which said traffic control circuit includes contact means controlled by said track circuits and closed only while said track circuits are energized, and in which each of said traffic governing devices is controlled by a corresponding one of said track circuits, the combination comprising, a plurality of neutral line relays one for each of said polar control relays connected in series with said polar control relays and said track circuit controlled contact means in said traffic control circuit, a back contact of each of said neutral line relays included in the control means for a corresponding one of said track circuits, a line relay repeater relay for each of said neutral line relays each controlled by a front contact of the corresponding neutral line relay, and front contacts of said line relay repeater relays connected in multiple with said track circuit controlled contact means in said traffic control circuit.

6. In railway traffic controlling apparatus for a stretch of railway track which is divided into a plurality of sections, embodying a plurality of polar control relays connected in series in a traffic control circuit, in which energization of said traffic control circuit including said polar control relays connected in series by current of normal and reverse polarities is manually controllable,

in which two track circuits are provided for each of given sections one for each direction of traffic movements, in which energization of each of said track circuits for a given direction of traffic movements is controlled by a contact of a corresponding polar control relay when closed in the normal position and energization of each of said track circuits for the opposite direction of traffic movements is controlled by a contact of a corresponding polar control relay when closed in the reverse position, 5 in which said traffic control circuit includes contact means controlled by a track circuit for each of said sections and closed only while the corresponding track circuit is energized, in which manual signal control devices and said track circuits control traffic governing means, the combination comprising, a plurality of neutral line relays one for each of said polar control relays connected in series with said polar control relays and said contact means, means controlled by said manual signal control devices upon being operated for controlling 10 said traffic governing means for deenergizing said traffic control circuit, and contact means controlled by a corresponding neutral line relay and closed when said neutral line relay is deenergized, said contact means being included in the control of each of said track circuits. 15 25 7. In combination, a stretch of railway track divided into sections, traffic governing means for governing traffic movements in a given direction and also in the opposite direction over said stretch of railway track, a plurality of polar control relays, a plurality of neutral line relays one for each of said polar control relays, traffic responsive means for each of said track sections including two track circuits for each of given track sections one for each direction of traffic movements, traffic responsive contact means for each of said sections controlled by 30 said traffic responsive means and closed in response to deenergization of said neutral line relays but becoming opened when the corresponding track section becomes occupied by a train, a traffic control circuit including said polar control relays, said neutral line relays, and said 35 traffic responsive contact means all in series; manually controllable means for effecting energization of said traffic control circuit by current of normal and reverse polarities, means controlled by back contacts of said neutral line relays and by normal and reverse polar contacts of said polar control relays for setting up the track circuits for said given track sections for traffic movements in a normal or a reverse direction respectively, 40 manually operable control means, means controlled by said traffic responsive means and by operation of said 45 traffic governing means for traffic movements in said normal or said reverse direction according as said normal or reverse polar contacts respectively of said polar control relays are closed, and means controlled by operation of said 50 manually operable control means for deenergizing said traffic control circuit. 55

8. In combination, a stretch of railway track, traffic governing means for governing traffic movements in a given direction and also in the opposite direction over 60 said stretch of railway track, a plurality of polar control relays, a plurality of neutral line relays one for each of said polar control relays, traffic responsive contact means for said stretch of track normally open but becoming closed in response to control by polar contacts of said polar control relays and by contacts closed in response to the deenergization of said neutral line relays, said traffic responsive contact means becoming opened in response to occupancy of said stretch of track by a train, a traffic control circuit including said polar control relays and said neutral line relays and also at times said traffic responsive contact means all in series, manually controllable means for energizing said traffic control circuit by current of normal and reverse polarities, manually operable control means, means controlled by said 65 manually operable control means and by normal and re- 70 75

verse polar contacts of said polar control relays for controlling said traffic governing means for governing traffic movements in a first direction or in the opposite direction respectively over said stretch of track, and means controlled by operation of said manually operable control means for deenergizing said traffic control circuit.

9. In combination, a stretch of railway track, traffic governing means for governing traffic movements in a given direction and also in the opposite direction over said stretch of railway track, a plurality of polar control relays, a plurality of neutral line relays one for each of said polar control relays, traffic responsive contact means for said stretch of track normally open but becoming closed in response to control by polar contacts of said polar control relays and by contacts closed when said neutral line relays are deenergized, said traffic responsive contact means becoming opened in response to occupancy of said stretch of track by a train, a normally energized traffic control circuit including said polar control relays, said neutral line relays, and said traffic responsive contact means in series; a line relay repeater relay for each of said neutral line relays, each said re-

peater relay being controlled by a front contact of the corresponding neutral line relay, front contacts of said line relay repeater relays connected in multiple with corresponding said traffic responsive contact means in said traffic control circuit, manually controllable means for energizing said traffic control circuit by current of normal and reverse polarities, manually operable control means, means controlled by said manually operable control means and by said traffic responsive contact means for controlling said traffic governing means for governing traffic movements over said stretch of track, and means controlled by operation of said manually operable control means for deenergizing said traffic control circuit.
